(57) **CLAIM**

The ornamental design for a medical coring device, as shown and described herein.

DESCRIPTION

FIG. 1 is a right side perspective view of a medical coring device in accordance with the present invention;

FIG. 2 is a front elevation thereof;

FIG. 3 is a right side elevation thereof;

FIG. 4 is a left side elevation view thereof;

FIG. 5 is a top plan view thereof;

FIG. 6 is a bottom plan view thereof;

FIG. 7 is a right side perspective of an alternative embodiment of the medical coring device in accordance with the present invention;

FIG. 8 is a front elevation of the embodiment depicted in FIG. 7;

FIG. 9 is a right side elevation of the embodiment depicted in FIG. 7;

FIG. 10 is a left side elevation of the embodiment depicted in FIG. 7;

FIG. 11 is a top plan view of the embodiment depicted in FIG. 7; and,

FIG. 12 is a bottom plan view of the embodiment depicted in FIG. 7.

The broken and dashed lines in FIGS. 1-3, 6-9 and 12 are for illustrative purposes only and form no part of the claimed invention.

1 Claim, 6 Drawing Sheets
